UNITED STATES PATENT OFFICE

JAMES H. FALLER, OF NEW ORLEANS, LOUISIANA

CRANK CASE VENTILATOR FOR ENGINES

Application filed March 5, 1930. Serial No. 433,357.

The object of my invention is to provide means to draw off all dilution in the form of vapor that accumulates in the base (crank case) of internal combustion engines, and a means for creating a suction for clearing fumes which are accumulated in the crank case, etc.

It is known that dilution is gasoline that does not burn in the combustion chamber, and passes the piston rings and thins the body of oil which results in a very poor lubrication in the engine. These vapors are carried either to the carburetor and burned, or thrown off under the car.

In the drawings:

Figure 1 is an outline side elevation of an engine equipped with my invention.

Figure 2 is a side elevation of my invention detached.

Figure 3 is a front elevation of Figure 2.

Figure 4 is a vertical central longitudinal sectional view of my attachment.

The reference numeral 5 designates an engine of approved type, having the usual fan 6 and breather pipe 7.

My attachment A is mounted on the breather pipe 7 and comprises a main body 8 semi-globular with an open front. In this body is positioned a tube 9, the lower end of which projects below the body 8, and is adapted to fit into the breather pipe 7 of the engine and support the attachment in operative position. The upper end 10 of the pipe 9 extends through and above the body 8. This has a detachable but air tight cover for the purpose of adding or filling the base with oil.

A tube 11 opens into and through the rear wall of the body 8 and extends rearwardly therefrom, to which is secured one end of the pipe 12 which discharges to atmosphere.

The pipe 9 has an opening through its rear wall, within the body 8, in which is secured one end of the tube 13, the other end of the tube 13 extending a substantial distance into the tube 11, and is equally spaced from the walls of the tube 11, as clearly seen in Figure 4.

As shown in Figure 1, my attachment is mounted on the breather tube and is positioned back of and near to the fan 6 with

the open end of the body 8 facing the fan, so that the air from the fan is blown directly into the body 8 around the tube 9, which is attached to the breather tube, the air currents passing rearwardly in the body 8 to 55 and through the restricted passage between the tubes 11 and 13 causes a vacuum at the free end of the tube 13 in the tube 11 which draws the vapors out of the engine base up through the tube 9, thence to the tube 13, 60 from which they are discharged into the tube 11, from which they pass to atmosphere through pipe 12.

It will be noted that by my invention air is not blown into the base to discharge the 65 vapors therefrom, but on the contrary the vapors are drawn from the base by the air from the fan or air which blows in through the radiator when the car is in motion, or by means of a special fan for that purpose only creating 70 a vacuum in the tube 11. This is an important feature in my invention, because when air from the outside is introduced into the base to force the vapors from the base it carries with it and introduces into the crank case 75 road dust which is positively injurious to the engine.

In the tube 11 I mount a butterfly or shut-off valve 14. This valve may either be thermostatically controlled or manually controlled. The function of this valve is to block, or partly block, the draft as may be desired, at times when it is not necessary to remove all or any of the dilution from the oil.

What I claim is:

1. An attachment for an internal combustion engine to draw the vapors from the crank case thereof; said attachment including a hollow body, a tube extending vertically through said body with its end portions projecting respectively beyond opposite sides of the body, one of said ends being adapted to communicate with the breather pipe of the engine, and telescoping tubes spaced from each other, one of which is in constant open communication 90 with said vertically extending tube.

2. An attachment for an internal combustion engine to draw the vapors from the crank case thereof; said attachment including a hollow body, a tube extending vertically through 100

- said body with its end portions respectively projecting beyond opposite sides of the body, one of said ends being adapted to communicate with the breather pipe of the engine, and telescoping tubes spaced from each other, one of which is in constant open communication with said vertically extending tube within said body, the other of which telescoping tubes is in constant communication with said body.
5. An attachment for an internal combustion engine to draw the vapors from the crank case thereof; said attachment including a hollow body, a tube extending vertically through said body with its ends respectively projecting above and below the same, one of said ends being adapted to communicate with the breather pipe of the engine and telescoping tubes spaced from each other, one of which is in constant open communication with said vertically extending tube, and a draft controlling valve in one of said telescoping tubes.
10. 3. An attachment for an internal combustion engine to draw the vapors from the crank case thereof; said attachment including a hollow body, a tube extending vertically through said body with its ends respectively projecting above and below the same, one of said ends being adapted to communicate with the breather pipe of the engine and telescoping tubes spaced from each other, one of which is in constant open communication with said vertically extending tube, and a draft controlling valve in one of said telescoping tubes.
15. 4. In a crank case ventilator for engines, a body of substantially semi-globular form having an open front, a tube extending vertically through said body with its end portions projecting respectively above and below the same, one of said ends being adapted to communicate with the breather pipe of the engine, a second tube extending from the rear 20 of the body and communicating therewith, a third tube communicating with the first tube and extending rearwardly therefrom into the second tube in spaced relation to the latter, and a controlling valve or damper in said second tube.
25. 5. An attachment for an internal combustion engine, to draw the vapors from the crank case thereof; said attachment comprising a hollow body, a tube vertically disposed within and spaced from the walls of the body with its ends extending respectively beyond opposite sides of the body, one of said ends being adapted to communicate with the breather pipe, a tube extending rearwardly from and
30. 40 through the rear wall of said body and in constant open communication with the body, a tube extending from the said vertical tube and telescopically disposed within and spaced from said rearwardly extending tube.
35. 45 50 In testimony whereof I affix my signature.

JAMES H. FALLER.
